SAMUEL P. WYRFEL, OF HARTFORD, CONNECTICUT, ASSIGNOR TO THE ARROW ELECTRIC COMPANY, OF HARTFORD, CONNECTICUT, A CORPORATION OF CONNECTICUT.

FACEPLATE FOR ELECTRICAL RECEPTACLES.

Application filed June 21, 1922. Serial No. 569,841.

To all whom it may concern:

Be it known that I, SAMUEL P. WYRFEL, a citizen of the United States of America, residing in Hartford, in the county of Hartford and State of Connecticut, have invented certain new and useful Improvements in Faceplates for Electrical Receptacles, of which the following is a specification.

My invention relates to face plates for electrical receptacles, and particularly to a face plate carrying a bull's eye jewel. The object of my invention is to provide an improved mounting for the jewel in the face plate.

15 In the accompanying drawings—

Fig. 1 is a plan view of a bull's eye face plate in which my invention is embodied in one form;

Figure 2 is a section on the line 2—2, 20 Fig. 1;

Fig. 3 is a similar view showing the plate partially formed, and the jewel in position for mounting;

Fig. 4 is an inverted plan of portion of 25 a face plate in readiness for the jewel mounting; and

Fig. 5 is a similar view after the jewel is mounted.

The present invention is applicable to 30 face plates for various types of receptacles, and may be embodied in what are known as combination plates, as well as in a simple bull's eye receptacle plate such as is here shown merely to illustrate the novel jewel mounting. The invention is applicable primarily to relatively thin sheet metal face plates rather than to the so-called solid plates.

As here shown the face plate 6 is apertured at 7 to receive the translucent bull's eye jewel 8. To afford a combined seat and mount for the jewel, the metal of the plate surrounding the aperture 7 is drawn by suitable dies, into a rearwardly extending collar 9. By a further operation, the metal is then offset at the front end of the collar to form a seat 10 against which the margin 11 of the jewel 8 rests in inserted position. After the jewel has been pressed

to its seat 10, the collar 9 is forced or spun over the bevel 12 of the jewel, thus firmly holding the latter to its seat in the plate. 50

As is well understood by those familiar with the art, a lamp is arranged behind the jewel, and light from this source passes therethrough. The present mounting is such that no peripheral opening remains between the jewel and the plate, through which light from the lamp may pass. The plate is more attractive for this reason than certain bull's eye plates now in common use, in which light leakage around the jewel occurs. The present mount is readily and economically effected, and is at the same time secure. 65

While the construction shown is simple, and the best known to me at the present time, modifications will readily occur to those dealing with the problem which do not depart from what I claim as my invention. 70

I claim—

1. A face plate for electrical receptacles, comprising a sheet metal plate having an aperture to receive a jewel, a seat for the jewel surrounding said aperture and faced toward the back of the plate, and rearwardly extending flange means integral with the plate for securing the jewel in said seat. 75

2. In a face plate for electrical receptacles, a face plate apertured to receive a jewel and offset at said aperture to form a seat, together with a rearwardly drawn collar integral with the plate and affording means for holding a jewel in position on said seat. 80

3. The method of mounting a jewel bull's eye in a sheet metal plate which consists in aperturing the plate, drawing a collar toward the rear of the plate from the metal surrounding said aperture, upsetting the plate metal at the aperture to afford a seat, mounting a jewel in said seat from the rear of the plate, and displacing the collar into engagement with the marginal portion of the jewel at the rear of the plate to hold the jewel to its seat. 90

In testimony whereof I have signed my name to this specification.

SAMUEL P. WYRFEL.
